WARP SIZING MACHINE

Charles B. Johnson, Paterson, N. J.

Application July 22, 1933, Serial No. 681,735

1 Claim. (Cl. 28—28)

In warp-sizing machines the warp after receiving liquid size travels in contact with a drying medium, as a series of rotary heated drums or "cans", being drawn through the machine by a take-up which usually includes means to beam the warp and which should coact with the drying medium to maintain the warp throughout the treatment in a certain degree of tension, to wit, that degree which is required by the particular warp being treated and which is essential to the particular product (the sized warp) which it is to form; in other words, if there is an inadvertent sudden and appreciable relaxation permitted trouble will be encountered and the quality of the product will be impaired. The operation is usually not stopped so as to bring the warp to a standstill once a particular warp has been started through the machine, since that involves leaving the warp standing in the sizing liquid of the sizing medium or quetch and the danger of harm being done to the warp while in stationary contact with the heated cans. What is done instead, when inspection or repair is necessary, is to slow down the machine to a relatively low speed for the time being. Heretofore there has been no provision for accomplishing this slowing down from and subsequent speeding up to the normal speed in a simple and quickly performable manner without incidentally producing appreciable relaxation of the tension of the warp, particularly when slowing down. Hence the object of this invention is to provide a machine of this class with means whereby a change in speed can be effected simply and quickly without relaxation of the tension.

In the drawings,

Figs. 1, 2 and 3 are, respectively, a plan, a side elevation and a front elevation of a warp-sizing machine embodying the invention;

Fig. 4 is a transverse sectional view of the take-up;

Fig. 5 is a section on line 5—5, Fig. 4;

Figs. 6 and 7 are, respectively, a plan and a front elevation of the change-speed mechanism, certain parts appearing in section;

Fig. 8 is a sectional view on line 8—8, Fig. 7, of the overrunning clutch, and Fig. 9 a transverse sectional view of such clutch; and

Fig. 10 is a view partly in elevation and partly in section of the other clutch.

On the frame 1 is arranged a quetch A, from which the warp receives sizing liquid, forward of the quetch are the rotary heated intergated cans B, and forward of the cans is the take-up C; there may also be a series of guide-bars D around

some or all of which the warp may extend in any arrangement. The take-up includes a beam on which the warp is wound and which is driven through slip-friction from a rotary impeller tending to rotate the beam at faster peripheral speed than that of the cans so that the warp will be tensioned between the take-up and cans; the take-up may include a set of nip-rollers which keep the warp flat and otherwise in proper order just prior to being wound on the beam. All this is, in a general may, known in the art. The quetch and cans are more particularly disclosed, for example, in my Patent No. 1,540,265. A more particular description of the take-up shown is as follows:

The beam 2 on which the warp is wound is supported between live and dead spindles 3 and 3a journaled, respectively, in a stand 4 and the frame 1. Splined to and therefore in effect one with the live spindle is a pulley-like element 5 having its flanges 5a faced with some friction material or otherwise adapted to afford friction surfaces. Freely revoluble on said element, as through the medium of anti-friction bearings 6, is a gear 7 having flanges 7a to coact with flanges 5a, and freely revoluble on the spindle both sides of element 5 are the disks or face-plates 8, the gear and disks being preferably interlocked as at 9 to rotate as one and constituting the mentioned impeller. This impeller being in rotation, the friction whereby element 5 and hence the spindle are driven is established by pressing one disk toward the other with consequent compression of each flange 5a between the gear and a disk-flange 7a. The left-hand disk abuts the stand 4, whereas the right-hand disk is subject to the pressure of a collar 10 slidable on the spindle, such collar being itself subject to the pressure of a lever 11 which is in turn subject to the pressure of a lever 12 having longitudinally adjustable weights 13, said levers being fulcrumed in the stand (Fig. 3). The weights having been adjusted on lever 12 to obtain a certain degree of slip-friction between the impeller and the driven member formed by 3—5 and the impeller being assumed to be driven at adequate speed the take-up will coact with the cans to tension the warp, such tension being regulable as the operation proceeds by adjustment of the weights. As for the nip-rollers, 14 is the lower one journaled in brackets 15 and 16 the upper ones resting on nip-roller 14 and having their gudgeons guided in slots in said brackets. The warp on its way from the bars D to the beam extends over one roller 16, under roller 14, and then over the other roll- 110

er 16. Nip-roller 14 carries a gear 17 meshing with gear 7 of the impeller. I provide cross-rails 18 on frame 1 which carry brackets 19 in which is journaled a shaft 20 having a pinion 21 meshing with gear 17, said shaft thus in effect forming one element of the rotary system constituting the take-up and with respect to a certain rotary shaft 29 to be referred to being what I term the driven element of said take-up.

10 Usually the cans are driven, as by a shaft 22 having a bevel-pinion connection 23 with shaft 20 and gearing 24 connecting the shaft with the near can. Due to the gear-ratio at 7-17 the tendency is for the take-up to rotate the beam 15 (through the mentioned slip-friction) at a faster rate than the cans, wherefore the beam coacts with the cans as indicated to tension the warp between the latter and the take-up, usually causing actual distention thereof and so setting up 20 such elastic force as is latent therein.

The power to drive shaft 20 is derived from an electric motor 25 and this, through gearing 26, a variable-speed transmission 27 (here of the well-known Reeves type) and gearing 28, drives a shaft 25 29 which in turn drives shaft 20 through either of two clutches 30 and 31, the former being an overrunning and the latter (here) a friction clutch, the constructions of which are as follows:

Clutch 30.—Clutch member 30a is free on the 30 shaft and clutch member 30b fast thereon. In a manner characteristic of this type of clutch, member 30a has peripheral notches 30c formed with inclined faces which converge toward the inner periphery of the flange portion of member 35 30b surrounding member 30a; in these notches and urged into such convergence by spring-plungers 30d are rollers 30e. When member 30a is rotated as per the arrow in Fig. 8 it will act through the rollers immediately to drive member 40 30b and hence the shaft, but member 30b and the shaft may be rotated faster than and hence independently of member 30a, as by clutch 31. Member 30a has affixed thereto a gear 32 in mesh with a pinion 33 fast on the shaft 29.

45 Clutch 31.—Clutch member 31a is free on the shaft, whereas clutch member 31b is keyed thereto. When a sleeve 31c is shifted to the right in Fig. 6 its wedge 31d spreads the dogs 31e which thereby expand the split-ring 31f into gripping 50 engagement with the encompassing portion of member 31a so that the shaft will then be adapted to be driven from the latter member. Member 31a has affixed thereto a pinion 34 in mesh with a gear 35 fixed on shaft 29.

55 The gear-ratios of the gearing connecting the two clutches with shaft 29 are such that shaft 20 will be driven at low speed when clutch 30 is active and at high speed when clutch 31 is active.

60 For shifting sleeve 31c of clutch 31a there is a lever 36 fulcrumed on one rail 18 and pivotally connected to a bar 37 slidable in brackets 38 on the frame 1. This bar and hence the lever and an operating handle 39 pivotally connected to the bar and fulcrumed in the frame may occupy any 65 of three positions determined by the engagement of a spring-pawl 40 in the frame with one of the notches 41, three in number, in the bar. The bar carries a projection 42 to press in a push-button 43 when the bar is in the position 0 (Fig. 7), thus to cut out the magnetic switch 44 for the motor 25 and so stop the machine, as upon completing a pass of the warp; when the bar is in the 70 position I or II (respectively for driving shaft 20 at slow speed through clutch 30 or at high speed

through clutch 31) the button is freed and closes the motor circuit.

The motor being here an electric motor, its power source is indicated at 45 and the circuit including the motor and switch 44 is shown at 46 partly in full and partly in broken outline.

In the operation of these machines, once a pass of warp is started there should, as explained, be no stopping until the pass is completed. What is done, instead, is to run the machine for the time being very slowly. This can not be done by resort to the variable-speed transmission 27 because the adjustment as to speed effected there is not intended to produce quick speed changes and once obtained should be preserved as much as possible, since it has much to do with the quality of the product (the sized warp) and depends largely on the skill and experience of the operator to determine it with that in view. For effecting a change from high to slow speed, and vice versa, the bar is shifted from position II to position I, or vice versa. When it is in position II (high speed) the drive is via gearing 35-34 and clutch 31; when the bar is in position I the drive is via gearing 33-32 and clutch 30. Only one clutch 10 (31) is manipulated. The other (30) automatically picks up shaft 20 or allows it to run ahead of it according as clutch 31 is placed out of or in commission. Besides the advantage thus present in the simplicity of construction and facility 10 of operation in changing the speed is an advantage which will be apparent when it is considered that if member 20 is cut off from the power and free to turn backward there will be nothing to oppose any effort of the warp to slacken, as due 11 to its weight between the take-up and cans or to the force of elasticity stored up in it between them, or both; in fact the potential extent of such slackening is equal to the sum of the back-lash increments existing in the gearing from the take- 11 up to the cans.

By my invention the cutting off of the power from the take-up and the consequent relaxation of the tension on changing from one speed to the other are avoided. This is quite as true when 12 the speed change is from high to low as when it is from low to high, and also when the machine is stopped by shifting lever 36 to position 0, for as soon as the high-speed clutch 31 ceases to exert torque on shaft 20 the low-speed clutch 30, without even momentary interruption, exerts its own torque on the shaft; in short, the shaft is at no time free to turn backward, thus to allow the slackening.

Consequently the invention makes it possible 13 for the machine to be run so as to pass the warp under any desired degree of tension, with quick changes from high to low speed and back, but continuously with tension present and in fact not varied in degree as an incident of the change. 13

I claim:

A warp sizing machine comprising, with a rotary means on which to wind the warp, rotary means having a slip-friction connection with and adapted to transmit rotation to the first means, and rotary heated means anterior to the first means resisting advance of the warp, a rotary driven element geared with the second and third means, a constantly rotating driving element, low-speed means to transmit rotary motion from the driving to the driven element including an overrunning clutch, and a disconductive high-speed connection to transmit rotary motion from the driving to the driven element. 14

CHARLES B. JOHNSON. 15
